UNITED STATES PATENT OFFICE.

LEMUEL FRITTS, OF SUNNY SIDE, NEW JERSEY.

DESIGN FOR A SHEAF-HOLDER.

SPECIFICATION forming part of Design No. 31,472, dated August 29, 1899.

Application filed June 12, 1899. Serial No. 720,331. Term of patent 3½ years.

To all whom it may concern:

Be it known that I, LEMUEL FRITTS, a citizen of the United States, residing at Sunny Side, in the county of Hunterdon and State of New Jersey, have invented and produced a new and original Design for Sheaf-Holders; and I do declare the following to be a full, clear, and exact description of the same, reference being had to the accompanying drawing, forming a part thereof.

My invention consists in a novel design for a sheaf or gavel holder to be attached to the delivery - board of a harvesting-machine or binder, and in the accompanying drawing I have illustrated my design.

The design consists of the rod or bar A, bent in wave form, as shown, said waves of uni-

form size, depth, and shape, excepting two shorter pivotal waves which engage in the fulcrums B B.

Other features of my design are the rod C, attached to one of the longer arms or waves of the holder, and the block D.

What I claim, and desire to secure by Letters Patent, is—

The design for a sheaf-holder substantially as herein shown and described.

In testimony whereof I affix my signature in presence of two witnesses.

LEMUEL FRITTS.
